UNITED STATES PATENT OFFICE.

HARRY A. ADAMS, OF NEW YORK, N. Y., ASSIGNOR TO HAMPTON HOGE, OF NEW YORK, N. Y.

STRIP-HANDLING APPARATUS.

Specification of Letters Patent.

Patented July 10, 1917.

1,233,157.

Application filed March 19, 1917. Serial No. 155,826.

To all whom it may concern:

Be it known that I, HARRY A. ADAMS, a citizen of the United States of America, residing at New York city, county and State of New York, have invented a new and useful Strip-Handling Apparatus, of which the following is a specification.

The main object of my invention is to provide a simple, inexpensive device for holding a roll of paper, cloth or other fabric in ribbon or strip form and delivering it in position so that it may be made adhesive and may be readily cut off.

Another object is to provide an apparatus of this character in which the roll of material is inclosed and protected.

Another object is to provide a simple and compact construction in which the material may be quickly and easily unwound and made adhesive and cut off.

In its preferred form the invention contemplates the use of a box or cabinet containing the roll of material in position so that only its upper edge is exposed. A roller for applying moisture or adhesive is located adjacent the upper edge of the roll of material. Between the roll of material and the roller is located a stationary edge for cutting off the strip. The roll of material is pressed upwardly by springs against the underside of the cover of a box. The cover is in the form of a slide and carries the cut off member.

Figure 1 is a plan view of apparatus embodying the improvements of my invention.

Fig. 2 is a vertical sectional view on the plane of the line 2-2 of Fig. 1.

Fig. 3 is a plan view of the cover.

Fig. 4 is a fragmentary transverse sec-

40 tional view on the plane of the line 4-4 showing the engagement between the cover, the sides of the box and the roll of material.

The roll 5 of material has a spindle 6 supported by plungers 7 on springs 8 at each 45 end of the spindle. The ends of the spindle are guided in grooves 9 in the sides of the box 10.

The cover 11 is guided in grooves 12 in the upper edges of the box. This cover has an opening 13 large enough to allow the end of the strip of material to pass out and provide an exposed portion 14 which can be engaged with the fingers for the purpose of rotating the roll and drawing out the strip.

55 The under side of the cover is preferably

cut out as at 15 to allow for the roll of material.

A receptacle 16 for the water or adhesive is located in the upper end of the box and provided with slots 17 for the spindle 18 of 60 the roller 19.

A cut off member or knife 20 is carried by one end of the cover 11 between the roll of material and the roll 19. The part 21 of the cover constitutes a support for the strip 65 and the cut off member 20 is raised just enough above the support 21 to permit the strip 22 to be drawn through.

To insert a roll of the material to be used the cover 11 is drawn outward to the right 70 as viewed in the drawing and the roll dropped into the box with the spindle 6 in the slots 9. The roll 5 is then pressed down against the pressure of the springs 8 far enough to permit the cover 11 to be slid in 75 place, as shown in Fig. 2. The pressure of the springs holds the roll pressed up against the under side of the cover and thus holds the cover in place. The end of the strip 20 80 may then be inserted under the member 20 and drawn over the top of the roll 19. If the strip has adhesive material already applied to it, it is merely necessary to provide water in the receptacle 16, but if the tape or strip has no adhesive material on it 85 then adhesive material would be supplied in the receptacle 16. The strip or tape is drawn across the top of the roll 19 until the desired length is made adhesive. The strip is then readily cut off by an upward pull 90 along the edge of the member 20. To remove the roll 5 it must be pressed down sufficiently to permit the cover to be drawn to the right.

By this inclosed type of apparatus the 95 material is kept clean and dry and yet always accessible for immediate use. By means of the springs 8, the entire roll is kept pressed upward to the orifice in the cover until the entire roll is used up.

I claim:

1. In a strip handling apparatus, the combination with a housing having an opening in its wall, an exposed strip severing blade 105 on the housing at one side of the opening in the wall thereof, a roll of strip material supported within the housing and having its leading end portion extended through the opening in the wall of the housing and passed beneath the strip severing blade at 110

the side of said opening, whereby such end portion of the strip is exposed and may be engaged by the finger to be thereby advanced beneath the strip severing blade and

5 a moistening device mounted in the housing in advance of the strip severing blade and arranged to be engaged by the advanced portion of the strip.

2. In a strip handling apparatus, the combination of a box having a movable cover with an opening in the upper part, a spring pressed roll of material mounted in the box and having one edge presented at said opening, a cut off member located adjacent said opening, and a roll adjacent said cut off member for making the strip adhesive.

3. In a strip handling apparatus, the combination of a box having a movable cover with an opening in the upper part, a spring pressed roll of material mounted in the box and having one edge presented at said opening, a cut off member located adjacent said opening, and a roll adjacent 25 said cut off member for making the strip adhesive, said cut off member being carried by said cover.

4. In a strip handling apparatus, the combination of a cover having an opening, 30 means for pressing one edge of a roll of material into said opening, a cut off member carried by said cover adjacent said opening and a roll adjacent said cut off member for making said strip adhesive.

35 5. In a strip handling apparatus, the combination of an inclosing box having guide ways for the spindle of a roll of material, a cover for said box having an opening, means for pressing a roll of material so as 40 to display one edge thereof through said opening, a cut off member adjacent said

opening and a roll adjacent said cut off member for making said strip adhesive.

6. In a strip handling apparatus, a member having an opening for the material to be handled, means for pressing the material through said opening, and a roll mounted at one end of said member for moistening said material.

7. In a strip handling apparatus, a member having an opening for the material to be handled, means for pressing the material through said opening, and a roll mounted at one end of said member for moistening said material, and a cut off member mounted 55 between said opening and said roll.

8. A strip handling apparatus, comprising a box, having an opening in the top thereof for supporting a roll of material within the box and pressing its upper edge 60 through the opening in the top thereof, a cut-off member mounted on the top of the box adjacent said opening and a moisture applying device mounted at the top of the box adjacent said cut-off member.

65 9. A strip handling apparatus comprising a box having a sliding cover with an opening therein, means for yieldingly supporting a roll of material within the box and pressing said material through said opening, a 70 cut-off member carried by said cover adjacent said opening and a moisture applying device carried by the box adjacent said cut-off member.

10. In an apparatus of the character described, a box having an opening, means for yieldingly pressing a supply of material through said opening, a moisture applying device carried by said box, and a support for the material extending from said opening to said device.

75 HARRY A. ADAMS.
